UNITED STATES PATENT OFFICE.

WILLIAM SIMPSON, JR., OF PHILADELPHIA, PENNSYLVANIA.

DESIGN FOR A PATTERN FOR PRINTED FABRICS.

SPECIFICATION forming part of Design No. 24,219, dated April 16, 1895.

Application filed October 19, 1894. Serial No. 526,420. Term of patent 3½ years.

To all whom it may concern:

Be it known that I, WILLIAM SIMPSON, Jr., a citizen of the United States, residing at Philadelphia, Philadelphia county, State of Pennsylvania, have invented a Design for a Pattern for Printed Fabrics, of which the following is a specification.

My present invention is a design for a pattern for printed fabrics.

10 In the accompanying drawing, I have illustrated a section of the fabric, showing my new design thereon.

The leading feature of my design consists in three figures, representing so-called typical "brownies," arranged symmetrically at the points of a triangle throughout the fabric.

15 Thus, referring to the drawing, A, represents a section of fabric, having on its face a figure B, representing a typical brownie Chinaman, a figure C, representing a typical brownie policeman, and a figure D, repre-

senting a typical brownie dude. These three figures are arranged symmetrically with relation to each other at the points of a triangle, the lines of the triangle not being shown in the design. This group of three figures, thus symmetrically arranged at the points of a triangle, constitute the essential features of my design, and this design will be repeated on the fabric, so that its surface is practically 3 covered.

I claim—

The design for a pattern for printed fabrics, substantially as shown.

In testimony whereof I have signed my name to this specification in the presence of two subscribing witnesses.

WM. SIMPSON, JR.
